J. BRANDWOOD ET AL
BLEACHING, DYEING, OR OTHER FLUID TREATMENT OF YARNS WOUND IN
THE FORM OF CHEESES
Filed Sept. 14, 1921

UNITED STATES PATENT OFFICE.

JOHN BRANDWOOD AND THOMAS BRANDWOOD, OF BURY, ENGLAND.

BLEACHING, DYEING, OR OTHER FLUID TREATMENT OF YARNS WOUND IN THE FORM OF CHEESES.

Application filed September 14, 1921. Serial No. 500,584.

To all whom it may concern:

Be it known that we, JOHN BRANDWOOD and THOMAS BRANDWOOD, subjects of the King of Great Britain and Ireland, and residents of Bury, in the county of Lancaster, England, have invented certain Improvements in and Relating to the Bleaching, Dyeing, or Other Fluid Treatment of Yarns Wound in the Form of Cheeses, of which the following is a specification.

In the specification to British Letters Patent No. 551 of 1913 granted to the present applicants and another, there is described and claimed an apparatus for the dyeing or analogous treatment of yarns wound upon hollow and perforated beams. Such apparatus, consists of a closed receptacle provided inter alia with a central rotatable shaft carrying at its upper end radial arms the free end of each of which arms is provided with screws which are adapted to screw down upon the end of a beam to close such end and press the other end of said beam upon a seat surrounding a liquor outlet. Liquid may be pumped through the yarn the centre of the hollow perforated beam and thence through the beam seat to be returned to the receptacle, or the direction of pumping may be reversed.

The apparatus referred to fulfils excellently the object for which it was designed, viz: the dyeing of yarns wound upon beams, each beam being one single unit placed within the dyeing kier. It is not however suitable for the dyeing of yarns wound in smaller units than a beam, for instance, cheeses, as such dyeing is at present carried out commercially, and this present invention has for object a form of container for yarn cheeses, with special disposition of the parts of said container which will allow of preliminary compression of the cheeses to a uniform density and the subsequent dyeing of the said cheeses in a beam dyeing receptacle of the type just referred to, a number of cheeses being packed within the container so that each container will form a single compact unit for placing upon a liquid tight seat of the dyeing receptacle. The upper end of each of the said units is arranged so that the screws carried by the radial arms may screw within the upper end of such unit to allow of the latter being

securely held whilst fluid is being circulated throughout the whole of the yarn of the cheeses.

Our invention will now be fully described with reference to the accompanying drawings wherein:

Figure 1 is a vertical section of the container with cheeses; and

Figure 2 a plan.

Referring to Figures 1 and 2, 1 is a bottom plate having formed therein the chamber 2 and provided with the tubular boss 3. 4 is a vertical rod secured to the upper face of the bottom plate 1 in any convenient manner; in the illustration it is shown as being screwed into an orifice in the upper part of the bottom plate 1 and secured in place by the nut 5. This vertical rod is screwed externally for approximately half of its length as shown, the thread being preferably a square thread, with a nut 6 fitted upon the said screwed portion. 7 are perforated tubes placed parallel to and symmetrically around the central rod 4, being secured to the upper surface of the bottom plate 1 in any known manner and opening into the chamber 2 of the said bottom plate. These perforated tubes may be of any suitable metal or alloy which will withstand the action of any liquid with which the cheeses may be treated and each of them is provided with a stopper 8 at its upper extremity. This extremity may be however permanently closed in any other convenient manner. 9 are cheeses fitted upon the said perforated tubes, and 10 a top pressure plate having screw eyes 11 for lifting purposes, and orifices formed therein to enable it to be slipped upon the central rod 4 and the perforated tubes 7. At its upper extremity the central rod 4 is internally threaded to receive the screwed shank of a ring handle 12.

In order to prepare the container with a number of cheeses for dyeing as a single unit in a dyeing receptacle of the type hereinbefore referred to, the ring handle 12 is removed and the nut 6 unscrewed from the central rod 4. The top plate 10 is then removed, and cheeses 9 are mounted upon each of the perforated tubes 7, one on top of the other, until the container is filled as shown in the drawing. The top plate is then passed over the central rod 4 and the tubes 7 and

rests upon the top cheeses. The nut 6 is then screwed upon the central rod 4 and screwed down tightly against the top plate 10, any desired compression being thus given to the cheeses. Owing to the nature of the winding of yarn in cheese form such compression is necessary for level treatment of all the yarn in a cheese with any fluid. The desired compression being attained by means of the nut 6, the ring handle 12 is screwed in place, and the container, now a single and compact unit, is lifted by said handle into the dyeing receptacle, the tubular boss 3 of the bottom plate 1 fitting upon the seat E as shown in the drawings of the British patent specification No. 551 of 1913. Six of the containers being thus prepared, the radial arms G of the specification referred to are brought round so that the free end of each arm is over a central rod 4. The screw J of the arm is then screwed down into the extremity of the said rod, the container thus being held securely for the dyeing operation and at the same time pressed down firmly on its seat E. Liquid may then be pumped into the receptacle at any convenient pressure above atmospheric and, when the receptacle is filled, the liquid will be forced radially inwards through the yarn of all the cheeses into the perforated tubes 7 and, the upper ends of these tubes being closed, will be forced into the chamber 2 of the bottom plate 1 and thence through tubular boss 3 back to the liquor tank. The flow of liquid may be reversed if desired.

The cheeses in the container may be treated with air or any other desired material after the liquor treatment, and when the whole operation is completed, the screw J may be released from the arm G moved away from the central rod 4. The ring handle 12 is then inserted, and the container is lifted from

the receptacle, for the removal of the cheeses therefrom.

By the use of a receptacle provided for six beams as shown in the prior specification: for the dyeing of six compact units composed of yarn cheeses as just described, a very large quantity of yarn in the form of cheeses may be dyed simultaneously, all of the cheeses being of uniform density and being treated at equal fluid pressure. Level dyeing and a reduction in dyeing cost are thus assured. If desired however, a less or greater number than six of these compact units may be treated simultaneously, according to the capacity of the receptacle.

What we claim as our invention and desire to secure by Letters Patent is:—

A container for yarn cheeses to be subjected to bleaching, dyeing or other treatment with fluids in a closed receptacle and at a pressure higher than atmospheric, said container comprising a bottom plate provided with an internal chamber, means for placing said bottom plate on a liquid tight seat around a liquor opening communicating with the said internal chamber, a central rod vertical to the bottom plate and adapted at its upper end to receive a lifting handle or alternatively screwing down means to press the bottom plate on its seat, vertical perforated tubes adapted to receive cheeses of yarn and opening to the internal chamber of the bottom plate, and a top pressure plate sliding on the central rod and tubes, with means for applying pressure thereto to compress the cheeses between the top and bottom plates to a uniform density.

In testimony whereof we have hereunto set our hands.

JOHN BRANDWOOD.
THOMAS BRANDWOOD.
